UNITED STATES PATENT OFFICE.

ALFRED RYDER AND ALFRED C. RYDER, OF SHEFFIELD, ALABAMA.

ADJUSTABLE HAT BLOCK.

Application filed December 10, 1923. Serial No. 679,570.

The present invention relates to certain new and useful improvements in hat blocks, and has for its object to provide a device of this character which embodies novel features 5 of construction whereby it can be easily and quickly adjusted to fit several different sizes of hats, thereby avoiding the necessity of carrying in stock a separate hat block for each of the many different sizes of hats.

10 Further objects of the invention are to provide an adjustable hat block which is comparatively simple and inexpensive in its construction, which can be easily and quickly adjusted, which is not liable to break or get 15 out of repair, and which provides a continuous smooth surface upon which to shape the hat which is being worked upon.

With the foregoing and other objects in view the invention consists in certain combinations and arrangements of the parts as will more fully appear as the description proceeds, the novel features thereof being pointed out in the appended claims.

For a full understanding of the invention 25 reference is to be had to the following description and accompanying drawings, in which,

Figure 1 is a top plan view of an adjustable hat block which is constructed in accordance with the invention, the smallest size 30 of the hat block being indicated by the full line positions of the parts while adjustments of the hat block to provide for two larger sizes of hats are indicated by dotted lines.

Figure 2 is a bottom plan view of the hat block mechanism proper showing the same as 35 detached from the base.

Figure 3 is a vertical sectional view taken on the line 3—3 of Figure 1, looking in the 40 direction of the arrows.

Figure 4 is an enlarged bottom plan view of the hat block mechanism when detached from the base, parts being broken away and shown in section to illustrate more clearly 45 the details of construction.

Figure 5 is a perspective view of one of the 50 filler elements which is adapted to be fitted in the spaces between the hat block sections when the hat block is expanded for one of the larger sizes of hats.

Figure 6 is an enlarged detail sectional view taken on the line 6—6 of Figure 3.

Figure 7 is a similar view taken on the line 7—7 of Figure 6.

55 Corresponding and like parts are referred to in the following description and design-

nated on all of the several views of the drawing by like reference characters.

Referring to the drawings which illustrate one of numerous possible mechanical embodiments of the inventive idea, the reference character A designates the hat block proper as a complete unit, and B the base upon which the hat block is supported when it is in use, the hat block being detachable 60 from the base so that different forms and shapes of hat blocks can be used upon the same base.

The block A has a hollow formation and is composed of a plurality of sections 1, 70 which are movable radially toward or away from each other to admit of the effective size of the hat block being adjusted to fit different sizes of hats. In the present instance there are four of the hat block sections 1, and the interior of each section is provided with an arm 2, said arms having their outer ends provided with ears 3 which are secured to the hat block sections, while the inner ends of the arms are slidably received within guide sleeves 4 which are carried by a plate 5. The guide sleeves 4 radiate from the axis of the hat block and the plate 5 is rotatable upon a tubular stem 6, which is arranged at the axis of the hat 80 block.

The arms or slides 2 are provided with downwardly projecting pins 7 which operate within longitudinal slots 8 in the guide sleeves 4 and extend through a set of eccentric or cam slots 9 formed in a lower plate 10 which is rigidly secured to the central stem 6. The lower end of the central stem 6 is received loosely within the upper end of a tubular standard 11 which is secured to the 95 base B. The tubular stem rests upon cross pieces 12 within the standard 11 and is formed with notches 13 which fit and interlock with the said cross pieces to hold the stem 6 against rotation within the standard. 100

When the hat block A is supported upon the base B, with the lower end of the stem 6 received within the tubular standard 11 and interlocking with the cross pieces 12, the body portion of the hat block can be 105 forcibly rotated relative to the base. The radial slides 2 which are carried by the hat block sections 1 cause the plate 5 to rotate upon the stem 6 with the hat block sections. The lower plate 10 is held against rotation, 110 being rigid with the central stem 6, so that this movement of the hat block body results

in a relative rotation of the superposed plates 5 and 10. The pins 7 are thus moved in the cam slots 9 of the lower plate 10, and this results in moving the pins radially in the longitudinal slots 8 of the guide sleeves 4 and simultaneously moving the slides 2 in or out depending upon the direction of rotation of the hat block body. When the slides are caused to move outwardly the hat block sections 1 are moved apart so that the effective size of the hat block is made larger. The same hat block can thus be adjusted to fit several different sizes of hats.

For the purpose of directing the hat block sections in their in and out movements, the meeting corners of the sections are provided with corresponding radial openings 14 which receive guide pins 15. In the present instance there are two of these guide pins 15 which engage the openings 14 of diagonally opposite sections 1. The guide pins may be loose in both of the openings or fastened in one of the openings and arranged to slidably engage the other opening, and it will be obvious that these guide pins serve to direct the sections 1 in their movements and keep them in proper position relative to each other.

When the sections 1 are moved apart and separated to provide a hat block for a larger size of hat, it is contemplated to insert filler strips 16, such as those shown by Figure 5, in the spaces between the sections. These filler strips are shaped so that the outer edges thereof will be flush with the top and sides of the hat block, thereby providing a continuous and uninterrupted surface for the outer working face of the hat block. It is contemplated to provide several sets of these filler strips 16 which are of different thicknesses, so that the size of the hat block will be determined by the particular set of filler strips which are clamped in position between the hat block sections. Two possible adjustments of the hat block are shown by dotted lines on Figure 1, and it will be obvious that the filler strips for the two adjustments would be of a different size and thickness. When the filler strips are in position the lower ends thereof rest upon plates 17 which are secured to the bottom of the hat block sections and arranged to span the gap between the sections. These plates extend across the joints between the sections, one end of each of the plates being secured to one of the sections, while the other end of the plate overlaps and frictionally en-

gages the other section. The filler strips are supported upon these plates 17 when they are initially placed in position, and are thereby held in proper position so that the outer edges thereof are flush with the outer surface of the hat block when the latter is rotated upon the base to cause the filler strips to be clamped between the hat block sections.

It will be obvious that this hat block can be readily adjusted to fit any of the various sizes of hats, and with the proper set of filler strips 16 in position the outer working surface of the hat block will be continuous so that the best results are possible in shaping and blocking hats.

Having thus described our invention what we claim as new and desire to secure by Letters Patent of the United States is,

1. An adjustable hat block including a hat block member formed in a plurality of complementary sections which are assembled around the axis of the hat block, means for moving the sections toward and away from each other to vary the effective size of the hat block, corresponding radial openings formed in the meeting corners of the hat block sections, guide pins fitted within the said openings and cooperating therewith to direct the hat block sections in their movements toward and away from each other, and plates applied to the bottom of certain of the hat block sections and extending slidably under adjacent hat block sections to assist in supporting the same in proper relative position.

2. An adjustable hat block including a hat block member formed in a plurality of complementary sections which are assembled around the axis of the hat block, means for moving the sections toward and away from each other to vary the effective size of the hat block, plates applied to the bottoms of certain of the hat block sections and extending across the joints between the sections into a sliding engagement with the lower face of adjacent sections, and a removable filler strip insertable between the sections and adapted to be initially supported by the said plates in position with the outer edges thereof flush with the outer surface of the hat block member.

In testimony whereof we affix our signatures.

ALFRED RYDER.
